VICTOR H. JACKSON, OF METUCHEN, NEW JERSEY, ASSIGNOR TO NEW YORK STOCK EXCHANGE, OF NEW YORK, N. Y.

CARRIER FOR PNEUMATIC DISPATCH SYSTEMS

Application filed September 2, 1931. Serial No. 560,697.

This invention relates to an improved form of carrier or container for pneumatic dispatch systems in which papers and other small objects are placed in a carrier or container which is transported from place to place in a system of tubing maintained under a suitable air pressure. 55

The use of carriers fabricated from metal, fibre and other materials has been proposed 10 for these systems and under certain special conditions such carriers have been more or less satisfactory in operation, but where a large number of such carriers are required their cost has been prohibitive. In certain 15 other installations, particularly where the carriers are necessarily small and vast quantities of them are necessary, the difficulties attending the use of such carriers have rendered their use impracticable. These containers have heretofore been constructed of 20 such material that when the carrier is subjected to an abnormal force, in any manner, it may be, and frequently is, permanently deformed. Thus a carrier may fall upon 25 the floor, and being unnoticed, is stepped upon so as to deform the carrier slightly and make it depart from its essential cylindrical cross section. Although this deformation may be so slight as not to be noticeable upon a hasty examination, it has been 30 found that when such a carrier is again placed in the system it frequently becomes jammed somewhere in the dispatch tubes, and temporarily, at least, renders that portion 35 of the system inoperative and may result in considerable inconvenience and expense. Needless to say, this expense is vastly greater than the cost of the particular carrier causing the trouble. 40

Heretofore it has been thought necessary to provide the ends of the carrier with felt or similar material adapted to contact more or less firmly with the inside surfaces of the tubes so as to prevent the passage of air 45 around the carriers, and provide bearing surfaces while keeping the central portion of the carrier of such diameter as would permit it to pass around bends in the tubes. A binding material is generally used to keep 50 the felt in position on the carrier. It will be appreciated that the construction of such carriers entails considerable expense and that a carrier of cheaper construction and resulting in a saving in operating expenses with increased efficiency is greatly to be desired. 55

Therefore, the principal object of the present invention is to provide a unitary carrier of material which does not retain a permanent deformation when subject to abnormal forces and in which the enlarged end portions are formed of the same, durable material as the body of the carrier. It has been found that carriers constructed of wood embody these provisions and may be constructed very cheaply; carriers made from birch wood combine the desirable qualities of ease of manufacture, durability and low cost. 60 65

Further objects of the invention will be apparent and the invention will be clearly understood from the following description and drawing in which 70

Fig. 1 is a perspective view of a preferred embodiment of the invention, 75

Fig. 2 is a longitudinal cross sectional view through the carrier,

Fig. 3 is a cross sectional view taken along the line 3—3 of Fig. 2, and 80

Fig. 4 is a longitudinal cross sectional view through a modified form of carrier. 85

In the drawing, the numeral 1 indicates the central or body portion of the carrier which, as before stated, may be, and preferably is, made of wood, such as, for example, birch. Each end of the body portion is provided with enlarged portions 2, formed integral therewith and of slightly less diameter than the inside diameter of the dispatch tubes. The diameter and length of the body portion and of the carrier in general are made such as to permit of the free passage of the carrier around the sharpest bend in the system. 90 95

Encircling each of the end portions are bands or strips of suitable fabric or tape 3, held thereto by an adhesive, or by other means. For example, ordinary moleskin, surgical, adhesive tape may be satisfactorily employed, or any tape of similar nature may 100

be used. Each band acts as a seal to prevent the passage of air between the end portions 2 and the inside surfaces of the dispatch tubes. As shown, the width of each band preferably corresponds with the length of the end portions 2 and thus more effectively prevents leakage of the air beyond the carrier when it travels around a bend when only the extreme ends of the carrier may be in contact with the tube.

A hole 4 of relatively large diameter extends almost through the carrier, leaving only a thin wall or closure 5 formed integrally with the other parts of the carrier, and thus providing the required space for the articles to be transported. The bands 3 of the two ends may suitably be distinguished by some external characteristics, such as color, so that the two ends of the carrier may be readily distinguished at a glance. Thus the band adjacent the open end of the carrier may be red, for example, and the band at the closed end white so that the operator in picking up a carrier which is lying on its side may always place the open end in position to receive a slip.

It will be readily understood by one skilled in the art that a wooden carrier of this form may be very easily and cheaply made in a few operations and that being constructed of wood, it will not retain a permanent deformation when subjected to pressure but will either return to its original form or, if the force applied be large enough, be crushed and rendered incapable of further use.

A typical carrier of the type just described may have an outside diameter at the reduced central portion of, say $61/64$ " while the outside diameter of the wooden portions at the ends may be $1\ 1/32$ ". The inside diameter may be approximately $13/16$ " while the overall length of the carrier may be $3\ 3/16$ ". Such a carrier is readily adapted to convey slips $3\frac{1}{2}$ " by 4" or even somewhat larger since the slips may extend a short distance beyond the end of the carrier without any difficulty.

Referring now to Fig. 4, there is shown a slightly modified form of carrier. In lieu of providing the carrier with a reduced central portion and enlarged ends, it may have substantially the same outside diameter throughout, insofar as the wood structure is concerned. A slight reduction in the diameter should, however, be made at one end so as to allow the carrier to readily travel around the bends in a line. The reduced portion 6, which may conveniently extend for about $5/8$ of an inch, is preferably located at the closed end of the carrier so that any tendency to weaken the construction will be offset by the strength added by the base 7. The outside diameter of the main portion 8 of this form should preferably be in be-

tween the diameters of the central and end portions of the first form of carrier disclosed. At the reduced end portion the outside diameter may suitably be $1/32$ of an inch less than for the main portion; the wall thickness throughout the main part may satisfactorily be made $5/64$ of an inch or possibly even $3/32$ of an inch. The base 7 may suitably have a thickness of about $3/16$ of an inch. A sturdier construction is thus produced, one which will resist to a greater degree the use and abuse to which these carriers are subjected. Furthermore, this type of carrier is somewhat simpler to manufacture than the first form since there is only a slightly reduced portion at one end. The tapes 9 and 10, preferably of different colors, may be applied in the same way to the two ends of the carrier.

It has been found from actual tests conducted over a period of a number of months that the average life of the improved wooden carriers is greater than that of fibre carriers. Fewer replacements have been required due to breakage or loss during the period of these tests than has been required during like periods when only the fibre type carriers have been employed. Furthermore, due to the lighter weight of the wooden carriers, they have been found to require less pressure and a correspondingly lower consumption of electrical power for driving the compressors than is required when fibre carriers are employed. It has also been found that the new carriers serve to assist materially in cleaning and polishing the interior of the tubes.

The invention is not to be limited to the use of wood since carriers may be made from other materials which possess the desired qualities without departing from the spirit and scope of the present invention.

What I claim is:

1. A carrier for pneumatic dispatch systems, comprising a substantially cylindrical body portion, enlarged end portions adapted to support the carrier within the tubing of the system, a closure at one end, said end portions and closure being formed integral with said body portion, said carrier being of material which does not retain a permanent deformation when subjected to pressure, and means encircling said end portions to prevent the passage of air around said carrier.

2. A carrier for pneumatic dispatch systems, comprising a substantially cylindrical body portion, enlarged end portions adapted to support the carrier within the tubing of the system, a closure at one end, said end portions and closure being formed integral with said body portion, said carrier being of material which does not retain a permanent deformation when subjected to pressure, and fabric bands suitably secured to, and encircling said enlarged portions to prevent the passage of air around said carrier, the

width of said bands being substantially equal to the length of said end portions.

3. As an article of manufacture, a carrier device for a pneumatic tube system comprising a cylindrical shell formed of material such as wood of such thickness and brittleness that when sufficient force is applied thereto to deform the same permanently and materially the shell will be fractured, 10 and a band of adhesive tape directly affixed to said shell adjacent either end.

4. A carrier for a pneumatic tube system comprising a cylindrical shell formed of wood and having a band of adhesive tape 15 directly affixed thereto adjacent each end, one end of said shell being of smaller external diameter than the other end.

5. A carrier for a pneumatic tube system comprising a cylindrical shell formed of 20 wood and having a band of adhesive tape directly affixed thereto adjacent each end, a portion of said shell having a reduced external diameter.

6. As an article of manufacture, a carrier 25 device for a pneumatic tube system comprising a cylindrical shell formed of material such as wood of such thickness and brittleness than when sufficient force is applied thereto to deform the same permanently and 30 materially the shell will be fractured.

In testimony whereof, I have signed my name to this specification this thirty-first day of August, 1931.
